UNITED STATES PATENT OFFICE.

DANIEL S. WILLIAMS, OF SALIDA, AND FREDERICK R. WATERS, OF OURAY,
COLORADO.

DESIGN FOR A HAMMER-HEAD.

SPECIFICATION forming part of Design No. 31,244, dated July 18, 1899.

Application filed June 24, 1899. Serial No. 721,783. Term of patent 14 years.

To all whom it may concern:

Be it known that we, DANIEL S. WILLIAMS, of Salida, in the county of Chaffee, and FREDERICK R. WATERS, of Ouray, in the county of Ouray, State of Colorado, citizens of the United States, have invented and produced a new and original Design for a Hammer-Head, of which the following is a specification, reference being had to the accompanying drawings, in which—

Figure 1 is a side view of a hammer-head, showing our new design. Fig. 2 is a plan view of the same, and Fig. 3 is a central cross-section.

15 The leading feature of our design is the

form of the groove or socket *a* in the side of the hammer-head, the same having a polygonal surface.

A minor feature of our design is the flare or enlargement *b* at the ends of the said groove or socket *a*.

What we claim is—

The design for a hammer-head, substantially as shown and described.

DANIEL S. WILLIAMS.
FREDERICK R. WATERS.
